D. J. KONTOLAMPROS.
ANTICREEPER AND SPREADLESS TIE PLATE.
APPLICATION FILED NOV. 15, 1916.

1,250,901.

Patented Dec. 18, 1917.

UNITED STATES PATENT OFFICE.

DEMETRIUS J. KONTOLAMPROS, OF SAN FRANCISCO, CALIFORNIA.

ANTICREEPER AND SPREADLESS TIE-PLATE.

1,250,901.

Specification of Letters Patent. Patented Dec. 18, 1917.

Application filed November 15, 1916. Serial No. 131,463.

To all whom it may concern:

Be it known that I, DEMETRIUS J. KONTOLAMPROS, a subject of Greece, residing in the city and county of San Francisco, State 5 of California, have invented a new and useful Anticreeper and Spreadless Tie-Plate, of which the following is a specification in such full and clear terms as will enable those skilled in the art to construct 10 and use the same.

This invention relates to an anti creeper tie plate and a spreadless tie plate, and its object is for the prevention of creeping and spreading of the rails upon a railroad track.

15 The advantages claimed by this invention over those now in use is the saw-tooth projections on the underside of the plate for inserting into the cross-tie members, thereby assisting the spikes in carrying the lateral stresses of the rails, called spreading, 20 and the corrugated lip portion parallel with the flange of the rail for preventing the rail from creeping.

With the ordinary tie plate which is used 25 in present track laying, the rail has a tendency to creep in the direction of the heaviest traffic. At the rail joint the angle bar connections have a slack, slots being provided in the angle bars for this purpose. As the 30 rail creeps, so will the ties near the joint portion, if they do not shear the spikes holding the rail down on the ties. Under the opposite rail the ties remain in the neutral position, as there is no anchorage of the rail 35 to the plates and ties. This condition will be the same in relation to other rail joints.

The above has been explained for the 40 benefit of those not familiar with the present situation of rail creeping. With the anti creeper tie plate, the object of this invention, there is the elimination of this 45 creeping as noted in the four anti creeper tie plates that are placed opposite the rail joints, therefore forming a rigid construction, and with the angle bars connecting both ends of the rails, these angle bars going 50 into the track bed, and fitted snugly against each tie, thereby makes the use of the anti creeper tie plates each side of the joint not necessary, and adds to the rigid construction at all the rail joints.

The foregoing and other objects of this 55 invention will hereinafter be more fully described, and claimed and illustrated in the drawings, forming a part of this specification, in which the same reference numerals

indicate corresponding parts in the different views throughout. However, I am aware that there may be many modifications thereof:—

60 Figure 1 is a plan view of a standard gage railroad track, broken away for the purpose of illustration at the rail joint.

Fig. 2 is a cross section on line 2—2 Fig. 1.

65 Fig. 3 is a perspective view of the anti creeper and spreadless tie plate showing the corrugated lip that prevents the rail from creeping.

Fig. 4 is a perspective view of the spread- 70 less tie plate, same as the anti creeper and spreadless tie plate, with the exception of slight modification in the construction, and without the corrugated lip portion.

Fig. 5 is an elevation of the anti creeper 75 and spreadless tie plate, showing the corrugated lip portion in the full width of the plate.

Fig. 6 is a modified form without the 80 underside tooth projections.

Numerals 1 and 2 indicate both rails of a railroad track which are held down by cross tie members, by means of the anti creeper and spreadless tie plates 4, and the spreadless tie plates 5, having the usual holes for 85 spiking. It is to be noted that Fig. 1 is a plan view at a rail joint, each joint of each rail being opposite the center of the opposite rail, which is generally the construction followed by track layers. At the rail 90 joint 6, there are two angle bars called anti creeper bars, indicated by 7 and 8, bolts 9, 10, 11, and 12 binding the rail and angle bars together. The spreadless tie plate 5 is used each side of the joints, as the angle 95 bars 7 and 8 tie the rail as the portions extending into the ground between the ties prevent moving of the rail longitudinally. It is to be understood that various spacing 100 may be adopted in placing of both anti creeper and spreadless tie plates, depending upon the nature of the grade of the track.

For example a mountain grade is shown in which the anti creeper and spreadless tie plate is used for every other tie until the rail 105 joint connections are reached, when the same application of both tie plates is used as noted in Fig. 1 and so on, but it is understood that on a level track, the spacing may be as many ties as preferable for the anti creeper and spreadless tie plates, in a general case as one in six or so ties, according to the judg- 110

ment of the track layers. It is to be further noted that the rail spikes bear upon the rail flange edge, and also against the saw tooth projections 15, 17, 18 and 20, on both tie plates, 16 and 19 being intermediate teeth. These projections inserted in the cross-ties 3, have their vertical faces toward the sides of the track as indicated in Fig. 4 and are braced by the angle back 17'. On the anti creeper and spreadless tie plate 4 the tooth projection 17 is slightly larger in width only, for the purpose of strengthening that portion of the tie plate, in which the corrugated portion of the lip 20' is under continual stress. The vertical face 16' on said tooth 17 is set slightly beyond the edge 21 of the recess for receiving the rail, which has the corrugated lip on the upper portion as already explained. On the spreadless tie plates the teeth are all the same proportion, and the tooth 20 is also set slightly beyond the shoulder 22 for strengthening that portion thereof. In the anti creeper and spreadless tie plate, three holes 23, 24, and 25 are used for spiking, and in the spreadless tie plates four holes are used, namely 26, 27, 28, and 29. But it is understood that any desired number of holes may be used for spiking the plates on cross ties 3. The material may be of any desired specification, as for example malleable, or alloy steel. This applies to the anti creeper and spreadless tie plates, and also to the spreadless tie plates, but the latter may be rolled from sheet steel through roll presses, and cut off crosswise of the teeth. The corrugated portion of the lip 20 may be of any shape desirable and hardened, and these teeth are to engage with the flange portion of the rail adjacent thereto when putting the rail into plate and lip recess. In Fig. 6 is shown a modified form of the anti creeper tie plate, in which 32 is the face of the plate that bears on ties, having the usual holes for spiking, and also the usual corrugated lip 35 extending the full width of plate. However, on the opposite side of the plate it may be understood that this lip may be of any width desirable on any of the forms. No

teeth projections are used on the underside 50 of the plate in this form.

Having thus described my invention, what I claim as new and desire to secure by Letters Patent of the United States, modifications being expressly reserved, is as follows:

1. In an anti-creeper and spreadless tie plate for a railway track, comprising a portion adapted to be interposed between the rail and the ties; said plate portion to be of the same width as the standard railroad ties; three wedge-shape ribs equally spaced on the underside and extending the full width of the plate; said ribs having an inclination on the same side; an extending lip portion the full width of the plate, the underside of said extending lip having a corrugated portion of V-shaped teeth inclined in the same direction as the flange of the rail, thereby forming a recess in which the rail flange is wedged onto the V-shape teeth and into the recess under the lip; and spiking apertures through the plate for securing the plate and the rail to the railroad ties.

2. In an anti-creeper and spreadless tie plate for a railway track, adapted to be interposed between the rail and the ties, comprising a flat plate portion having spiking apertures therein for securing the plate and the rail to the ties; three inclining ribs equally spaced apart on the underside and the full width of the plate; an extending lip portion on the opposite side the full width of the plate; said lip forming a recess adaptable to receive the base flange of a railway rail; said lip having a corrugated portion of V-shape teeth on the underside thereof; and the shoulder of said recess being beyond the vertical side of one of the ribs on the opposite side of the plate.

In testimony whereof I have hereunto set my hand on this 12th day of November, A. D. 1917, in the presence of the two subscribed witnesses.

DEMETRIUS J. KONTOLAMPROS.
